UNITED STATES PATENT OFFICE

RAYMOND C. DAVID, OF CLINTON, MASSACHUSETTS

SEWING MACHINE ATTACHMENT FOR MAKING BUTTONHOLES

Application filed November 21, 1929. Serial No. 408,833.

This invention relates to attachments for sewing machines and more particularly to devices of this character which are adapted to be attached to a conventional type of machine for the purpose of sewing buttonholes, and has, for one of its purposes, the provision of a machine of this character which will perform all of the operations necessary to attain a completely sewed buttonhole.

10 Another object of the invention is to provide, in a manner as hereinafter set forth, a button hole sewing attachment of the aforementioned character which may be expeditiously adjusted in a manner to adapt same 15 for operation on buttonholes of varying lengths.

Other objects of the invention are to provide a buttonhole sewing attachment of the character described, which will be simple in 20 construction, strong, durable, efficient in its use, and which may be manufactured at low cost.

Other objects and advantages of the invention will become apparent from a study 25 of the following specification, taken in connection with the accompanying drawings, wherein like characters of reference designate corresponding parts throughout the several views, and wherein:

30 Figure 1 is a front elevation of a button hole sewing attachment for sewing machines constructed in accordance with this invention.

Figure 2 is a rear elevational view thereof.

35 Figure 3 is a top plan view.

Figure 4 is a bottom plan view thereof.

Figure 5 is a vertical sectional view looking from the front to the rear thereof and wherein the front wall of the casing, together with the ratchet discs has been removed.

40 Figure 6 is a vertical sectional view looking from the front to the rear of the machine and similar to Figure 5 with the exception 45 that the segmental ratchet plate is mounted in place adjacent the cam plate.

Figure 7 is a vertical sectional view looking from the front to the rear of the machine 50 with the front wall of the casing, both of the

ratchet discs, and the master cam removed therefrom.

Figure 8 is a vertical sectional view of the device with the front wall only of the casing removed therefrom. 55

Figure 9 is a view in side elevation of the driving mechanism of the device, the elements thereof being separated for the purpose of clearness.

Figure 10 is a perspective view of the actuating means for shifting the foot of the machine laterally. 60

Figure 11 is a perspective view of one of the cams forming a part of the drive mechanism. 65

Figure 12 is a detail view in perspective of the pivotally connected, spring controlled pawls which engage the ratchet discs.

Figure 13 is a top plan view of the carrier plate which supports the foot. 70

Figure 14 is a view in perspective of the oscillating arm which is pivotally connected at one end to the device and adapted for engagement with the sewing machine for actuating the same. 75

Figure 15 is a detail view in perspective of the pawl which is mounted on the lever shown in Figure 14.

Figure 16 is an end elevation of the cam which is provided with laterally projecting pins for engagement with the pawl shown in Figure 15 for rotating said cam. 80

Figure 17 is a detail perspective view of the supporting shaft for the driving element. 85

Figure 18 is a detail view in perspective of one of the ratchet plates or discs.

Figure 19 is a detail view in perspective of the connecting rod which couples the ratchet discs to the foot plate. 90

Figure 20 is a detail view in perspective of the cam which is pivoted in the casing of the device and is adapted to engage the cam illustrated in Figure 11 of the drawings. 95

Figure 21 is a detail view in perspective of the securing element for retaining the device in adjusted position when same has been regulated for work on buttonholes of different lengths. 100

Figure 22 is a detail view in perspective of what will hereinafter be termed the master cam.

Figure 23 is an elevation of the ratchet plates secured together.

Figure 24 is a view in end elevation of the foot plate.

Referring to the drawings in detail, the reference character 1 designates generally a casing comprising a front wall 2, an upper wall 3, and a rear wall 4. An end wall 5 has mounted on its upper portion a clamping sleeve 6 for attachment to the sewing machine, and in which is threaded a set screw 7 for the purpose of securing same.

A vertically swingable arm 8 is pivotally connected, as at 9, to the rear end of the casing 1 on the inner side of the rear wall 4 thereof and extends forwardly through a vertical slot between said plate 4 and end wall 5 and extends beyond the front end of said casing and is provided, at its free end, with a separable bifurcated end piece 10, which is detachably secured thereto through the medium of the securing elements 11. The purpose of the detachable bifurcated end piece 10 is to permit the use of the bar 8 for connection with variously sized hubs of different sewing machines.

As seen most clearly in Figures 9 and 7 of the drawings the casing 1 is provided with a central web or partition 12 through the central portion of which extends a shaft 13 which is illustrated in detail in Figure 17 of the drawings. The shaft 13 is provided with a threaded bore at one end for the reception of a headed retaining screw 14 and intermediate its ends, said shaft is provided with an annular flange 15 which abuts the forward face of the partition 12 of the casing.

Rotatably mounted on the rear portion of the shaft 13 adjacent the partition 12 of the casing, is a cam 16 which is provided with an opening 17 adjacent its marginal edge. This cam is shown in detail in Figure 11 of the drawings. A disc 18 is mounted on the outer portion of the shaft 13 and is coupled to the cam 16 through the medium of a laterally projecting pin 19 which extends into the opening 17 of the said cam.

As seen most clearly in Figure 16 of the drawings, the peripheral edge of the disc 18 is provided with a circumferentially extending cam groove 20 and the rear face of the disc has mounted thereon an annular series of laterally projecting pins 21. The disc 18 and the cam 16 are retained for rotation on the shaft 13 through the medium of the retaining screw 14. The arm 8 has mounted thereon, an upwardly extending spring controlled pivoted pawl 22 having a notched upper end portion for successively engaging the pins 21. It will thus be seen that the disc 18, together with the cam 16 which is coupled thereto through the medium of the pin 19 ex-

tending into the opening 17, will be rotated in a step by step manner when the arm 8 is oscillated in a vertical plane.

The partition 12 of the casing is provided with an opening 23, see Figure 7 of the drawings, and a horizontally disposed transversely extending shaft 24 extends through said opening and is supported at its opposite ends, in the front and rear walls 2 and 4 of said casing. An oscillating double ended pawl 25 is 70 rockingly mounted on the shaft 24 through the medium of a tubular sleeve 26 extending through the intermediate portion of said pawl for the reception of said shaft. The lower end of the pawl 25 is provided with a 75 rounded head 26 for engagement with the peripheral edge of the cam 16 and is maintained in engagement therewith through the medium of an integral leaf spring 27 having its free end engaged against the rear wall 3 of 80 the casing.

Adjacent its upper end, the pawl 25 is provided with a laterally projecting horizontal pin 28 and pivotally mounted thereon are a pair of oppositely extending dogs 29 and 30. 85 The free ends of the dogs 29 and 30 are constantly urged downwardly through the medium of an arcuate spring 31 which is rigidly secured to one of said dogs, and has its free end in engagement with the other and 90 is normally of greater curvature than when in position on said dogs.

A cam 32 is rotatably mounted on the flange 15 of the shaft 13 and is provided, at its rear portion, with a horizontally disposed laterally extending shank 33 which extends through a slot 34 in the wall 2 of the casing and constitutes means for manually rocking said cam on its support. Rotatably mounted on the shaft 13, adjacent the cam 32 is a segmental 100 ratchet plate 35 having a section of its arcuate peripheral edge provided with the ratchet teeth 36 for engagement with the dog 30.

A ratchet disc 37 is rotatably mounted on the shaft 13 in abutting relation to the segmental plate 35 and said disc 37 and the plate 35 are each provided with a series of horizontally aligned openings 38. The cam 32 is provided with an arcuate slot 39 and a pin 40 extends through a pair of the aligned openings at the forward ends of the series of openings in the ratchet discs and protrudes into the slot 39 of the cam 32. The disc 37 is provided with ratchet teeth on the portions of its marginal edge which are reversed with respect to the teeth on the segmental plate 35 and are for engagement with the dog 29.

The shaft 13 projects centrally through an opening 42 in the front wall 2 of the casing and extends outwardly therefrom and is provided with an annular groove or channel 41 adjacent its outer end. As seen in Figure 1 of the drawings, the wall 2 of the casing is provided with an arcuate series of indicating numerals which are arranged concentrically 105

with respect to the opening 42 and indicate the ordinals of the openings 38 consecutively from 2 to 7. An arm 43 is detachably mounted on the protruding end of the shaft 13 and has mounted on its free end a laterally extending pin 44 adapted to be selectively inserted through the aligned openings 38 in the ratchet elements and protrudes into the slot 39 of the cam 32. In this manner, the independent rotation of the ratchet elements on the shaft 13, with respect to the cam 32 is limited by reason of the pins 40 and 44 engaging the opposite ends of the slot 39. A spring detent (not shown) seats in channel 41 for detachably securing arm 43 on shaft 13.

A laterally shiftable plate 45 is mounted on the bottom of the casing 1 and the longitudinal marginal edges thereof are provided with down-turned dove tailed channel forming portions in which a foot plate 46 is mounted for longitudinal sliding movement. A coupling rod 47 is pivotally connected as at 48, to the ratchet disc 37 at a point thereof which is free of the adjacent ratchet plate 35 and said rod extends between said disc 37 and the cam 32.

As seen in Figure 19 of the drawings, the opposite end of the coupling 47 is provided with a laterally extending pin 49 which extends slidably into the slot 50 in the lower end of the wall 2 of the casing for the purpose of supporting that end of the coupling rod. The coupling rod 47 is also provided at its lower end with a downwardly extending shank 51 which protrudes through an elongated opening 52 in the carrier plate 45 and projects into an opening 53 in the foot 46.

A lever 57, see Figures 2 and 10 of the drawings, is provided with a thickened base portion 58 having a vertical bore 59 extending therethrough for the passage of a pivot pin 60 for pivotally mounting the lever 57 on the casing 1 in a manner to swing in a horizontal plane. The free end of the lever 57 is provided with a vertical lug or protuberance 60 which extends into the cam groove 20 of the disc 18 for the purpose of oscillating said lever upon actuation of said disc 18.

A spring rod or wire 61 has one end anchored in the base portion 58 of the lever 57 and extends parallel therewith for engagement with a substantially key-shaped bar 62 on the carrier plate 45.

The bar 62 is mounted for reciprocation in the key-hole shaped opening A in the casing 1 and constitutes means for mounting the carrier plate on the bottom wall B thereof. The upper portions of the bar 62 are removed, as shown in Figure 6 to permit the rotatable elements on the shaft 13 to pass and said bar is provided with notches C and D on its opposite sides and at different longitudinal points (see Figure 13) for the reception of the stop lugs E and F on the cam 32. The lugs E and F travel in the groove G in the casing 1. A

transverse slot H is provided in the carrier plate 45 and a headed screw I is threaded into the bottom B of the casing and has its head disposed in the slot for preventing lateral displacement of the plate from the casing at all times. A spring pressed dog K is pivotally mounted in the casing 1 for engagement in the recess L in cam 32 for a purpose to be presently set forth. The foot plate 46 is provided with pairs or rows of gripping teeth 63 at its forward end and the forward end of said foot plate is bifurcated as at 64, as seen most clearly in Figure 4 of the drawings.

As illustrated in Figure 24, these gripping teeth 63, have pointed free ends, formed by providing an outer wall extending at right angles to the foot plate, with the other side wall inclined.

When the arm 8 is oscillated in a vertical plane, the spring controlled pawl 22 successively engages the pins 21 on the disc 18 and said disc is thereby rotated in a step-by-step manner. This movement is transmitted to the cam 16 through the medium of the pin and hole connections between said cam and the disc and the oscillating pawl 25 which is engaged with said cam through the medium of the spring 27 is rocked upon the shaft 24.

When the upper end of the pawl 25 swings downwardly the spring-pressed dog 30 thereon engages the teeth on the segmental ratchet plate 35 and rotates the same in a clockwise direction a distance of one tooth at a time. Being coupled to the ratchet disc 37 through the medium of the pin 40, this movement is transmitted to said disc 37 and as a result, the foot plate 46 will be moved to its retracted position as shown in the drawings, through the medium of the connecting rod 47.

When the pin 40 engages the forward end of the slot 39 in the cam 32, said cam will be caused to rotate therewith a very slight distance which movement brings a raised peripheral portion of the cam into engagement with the dog 30 and lifts same out of engagement with the teeth on the ratchet plate 35 and both dogs 29 and 30 are retained elevated out of engagement with their respective ratchet. The dogs are retained in this elevated or neutral position through a period of the operation of sewing a buttonhole, after which, the arm 33 is elevated to move the cam 32 and permit at the same time, a low portion of the peripheral edge of the cam to pass the free end of the dog 29 and permit said dog to drop into engagement with the teeth on the ratchet disc 37 and said disc, together with the segmental plate 35 will be thus rotated in an anti-clockwise direction for shifting the foot plate 46 forwardly.

This reverse movement is continued until the pin 44 engages the opposite end of the slot which will cause the cam 32 to again shift and raise the dog 29. For the purpose of adapting the machine to buttonholes of

varying lengths, the distance of the forward and rearward travelling stroke of the foot plate 46 may be regulated by placing the pin 44 in any one of the openings 38 and thus varying the distance which the ratchet plates may rotate independently of the cam 32.

When the fabric in which the buttonhole is to be sewed is properly positioned beneath the foot 46 of the device, the arm 33 is raised manually to the upper end of the slot 34 in the casing 1 and the cam 32 is thus moved so that the dog 29 engages the ratchet wheel 37 and the stop lug F on said cam is shifted into the notch D of the T-shaped bar 62 on the carrier plate 45.

The lateral motion of the carrier plate is thus limited, by the stop lug F in the notch D to the length of the stitches on the side of the buttonhole. When the foot plate 46 reaches the reversing point, cam 32 has been moved in an anti-clockwise direction a sufficient distance to withdraw the stop lug F from the notch D and the foot plate is permitted to reciprocate laterally together with the carrier plate 45 for the full distance of the slot H in said carrier plate for forming the bar stitching at that end of the buttonhole, and at least four bar stitches are made before the actual reverse stroke begins, at which time the spring pressed dog K slips over the adjacent corner of the notch L in the cam 32 and snaps said cam 32 into reverse position, moving the stop lug E thereon into the notch C on the bar 62 for regulating the length and position of the stitches for the other side of the buttonhole on the reverse longitudinal stroke of the foot 46.

When the reverse end of the buttonhole is reached the parts are in the position shown in Figure 8 of the drawings wherein the stop lug E has been moved out of the notch C and the dogs 29 and 30 have been lifted off of the ratchet wheels or discs to a neutral or non-operating position, plate 45 is again allowed to move the full length of the bar stitching as long as desired.

When it is desired to start the sewing of another buttonhole, the arm 33 is manually lifted to the top of the slot 34 and the foregoing operation is repeated.

It will be apparent that the stroke of the footplate 46 will be shortened by placing the pin 44 through the openings which are nearest the end as this would considerably limit the rotation of the ratchet plates or discs with respect to the cam.

It is believed that the many advantages of a device constructed in accordance with this invention will be readily understood, and although the preferred embodiment of the invention is as illustrated and described, it is to be understood that changes in the details of construction may be had which will fall within the scope of the invention as claimed.

What is claimed is:

1. A sewing machine attachment of the character described comprising a casing, a work engaging and shifting foot mounted for reciprocation on the casing and means for actuating said foot comprising an oscillating lever engaged with the machine for actuation, a rotatable disc having a series of laterally projected spaced pins mounted for rotation on the casing, a pawl mounted on the lever and adapted to successively engage the pins when the lever is oscillated in a manner to rotate the disc in a step-by-step manner, a cam mounted for rotation on the casing and coupled to the disc, a pair of ratchet elements mounted for rotation in the casing, means actuated by the cam and engageable alternately with the ratchet elements for alternately rotating same in opposite directions and a coupling rod connected to the ratchet elements and to the foot.

2. In a sewing machine attachment of the character described comprising a casing, a work engaging and shifting foot mounted for reciprocation on the casing, and means for actuating said foot comprising an oscillating lever engaged with the machine for actuation, a rotatable disc having a series of laterally projected spaced pins mounted for rotation on the casing, a pawl mounted on the lever and adapted to successively engage the pins when the lever is oscillated in a manner to rotate the disc in a step-by-step manner, a cam mounted for rotation on the casing and coupled to the disc, a pair of ratchet elements mounted for rotation in the casing, an oscillating pawl mounted on the casing and engaged with the cam, means mounted on the pawl for alternately engaging the ratchet elements for rotating same alternately in opposite directions, and a coupling rod connected to the ratchet elements and to the foot.

3. A sewing machine attachment of the character described comprising a casing, a work engaging and shifting foot mounted for reciprocation on the casing, and means for actuating said foot comprising an oscillating lever engaged with the machine for actuation, a rotatable disc having a series of laterally projecting spaced pins mounted for rotation on the casing, a pawl pivotally mounted on the lever and adapted to successively engage the pins when the lever is oscillated in a manner to rotate the disc in a step-by-step manner, a cam mounted for rotation on the casing and coupled to the disc, a pair of ratchet elements mounted for rotation in the casing, an oscillating pawl mounted on the casing and engaged with the cam, a pair of dogs pivotally mounted on the oscillating pawl and engageable alternately with the ratchet elements for rotating the same alternately in opposite directions and a coupling rod connected to the ratchet elements and to the foot.

4. A sewing machine attachment of the character described comprising a casing, a work engaging and shifting foot mounted for reciprocation on the casing and means for actuating said foot comprising an oscillating lever engaged with the sewing machine for actuation thereby, a rotatable disc having a series of laterally projecting spaced pins mounted for rotation on the casing, a pawl mounted on the lever and adapted to successively engage the pins when the lever is oscillated in a manner to rotate the disc in a step-by-step manner, a cam mounted for rotation on the casing and coupled to the disc, a pair of ratchet elements mounted for rotation in the casing, an oscillating pawl mounted on the casing and engaged with the cam, a pair of dogs pivotally mounted on the oscillating pawl and engageable alternately with the ratchet elements for rotating same alternately in opposite directions, a cam rotatably mounted in the casing, and having means for coaction with means on the ratchet elements for rotating the cam, said cam being adapted to engage the dogs in a manner to alternately engage and disengage same with the ratchet elements, and a coupling rod connection to the ratchet elements and to the foot.

5. A sewing machine attachment of the character described comprising a casing, a work engaging foot plate mounted for lateral and longitudinal reciprocation on the casing, a disc mounted for rotation in the casing having a cam groove in its peripheral edge, means mounted on the casing and engageable with the sewing machine for rotating the disc, means mounted in the casing and actuated by the disc for shifting the foot plate longitudinally and means mounted in the casing and actuated by the disc for reciprocating the foot plate laterally and comprising a laterally shiftable supporting plate for the foot plate mounted on the casing, a lever pivotally connected, at one end, to the casing and having its free end disposed in the cam groove of the disc for oscillation thereby and a resilient rod rigidly mounted on the lever adjacent its pivoted end for movement therewith, said rod engaging the supporting plate in a manner to reciprocate same laterally on the casing.

6. A sewing machine attachment of the character described comprising a casing, a foot plate mounted on the casing comprising a body portion having a bifurcated forward end and pairs of rows of fabric engaging teeth mounted on the furcations the outer side of each of said teeth extending at a right angle to the foot plate and the other side thereof being inclined, said fabric gripping teeth having pointed free ends.

7. A buttonhole sewing attachment for sewing machines comprising a casing, a vertically moving arm pivotally mounted in said casing and connected to a moving part of the

sewing machine mechanism, a shaft mounted in said casing, a cam member mounted on said shaft, means for rotating said cam member from said vertically movable pivoted arm, and including a disk coupled with the cam member and having a cam shaped peripheral groove, a pair of ratchet wheels carried by the shaft, a pivoted pawl operated by the cam shaped peripheral groove, a pair of dogs carried by said pivoted pawl and adapted to alternately engage said ratchet wheels by pivotal movement of the pawl, a second cam for determining the engagement of said dogs with their respective ratchet member, a work engaging and shifting foot mounted for reciprocation in the casing, and means for operating said work engaging and shifting foot from one of said ratchet members.

In testimony whereof I affix my signature.
